UNITED STATES PATENT OFFICE.

STANLEY H. BARNES, OF NEW ROCHELLE, NEW YORK, ASSIGNOR TO GLEASON-TIE-BOUT GLASS COMPANY, OF NEW YORK, N. Y., A CORPORATION OF NEW YORK.

DESIGN FOR AN ILLUMINATING GLASS SHADE.

Application filed June 8, 1927. Serial No. 22,363. Term of patent 7 years.

To all whom it may concern:

Be it known that I, STANLEY H. BARNES, a citizen of the United States, residing at New Rochelle, in the county of Westchester and State of New York, have invented a new, original, and ornamental Design for Illuminating Glass Shades, of which the following is a specification, reference being had to the accompanying drawing, forming part thereof.

Fig. 1 is a side elevation and Fig. 2 is an inverted plan, or bottom view, of an illuminating glass shade, showing my new design, the essential features of which are the proportions, and the concavo-convex closed bottom.

I claim:

The ornamental design for an illuminating glass shade, as shown and described.

STANLEY H. BARNES.
